US0D1049198S

(12) **United States Design Patent** (10) Patent No.: **US D1,049,198 S**
(45) Date of Patent: ** Oct. 29, 2024

(54) **WIRELESS BACKUP CAMERA**

(71) Applicant: **Shenzhen Auto-vox Technology Co., Ltd**, Shenzhen (CN)

(72) Inventor: **Feng Guo**, Guangdong (CN)

(73) Assignee: **SHENZHEN AUTO-VOX TECHNOLOGY CO., LTD**, Shenzhen (CN)

(**) Term: **15 Years**

(21) Appl. No.: **29/956,324**

(22) Filed: **Aug. 7, 2024**

(51) LOC (14) Cl. **16-01**

(52) U.S. Cl.

USPC **D16/208**

(57) **CLAIM**

The ornamental design for a wireless backup camera as shown and described.

DESCRIPTION

FIG. 1 is a front view of a wireless backup camera showing my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a top, right front perspective view thereof; and,

FIG. 8 is bottom, left rear perspective view thereof.

The broken lines depict portions of the wireless backup camera that form no part of the claimed design.
